E. H. BOBO

SWINGING DOOR STOP

Filed August 12, 1925

Patented May 4, 1926.

1,583,650

UNITED STATES PATENT OFFICE.

EDWARD H. BOBO, OF RANGER, TEXAS.

SWINGING-DOOR STOP.

Application filed August 12, 1925. Serial No. 49,773.

To all whom it may concern:

Be it known that I, EDWARD H. BOBO, a citizen of the United States, and a resident of Ranger, in the county of Eastland and State of Texas, have invented certain new and useful Improvements in Swinging-Door Stops, of which the following is a specification.

This invention relates to a door prop.

The purpose of the invention is to provide a door prop which is inexpensive to manufacture and adapted to be applied to doors which at times it is desired to maintain in open position such as hinged doors used on a garage or the like.

It is also within the scope of the objects of the invention to provide a door prop which can be easily manipulated and which will maintain itself in an unobstructing position when not in use.

Other objects relating to details of construction, combination and arrangement of parts will hereinafter appear.

The invention is illustrated by way of example in the accompanying drawings, in which;—

Figure 1 is a partial perspective view of a garage and showing my invention applied,

Figure 2 is a detail plan view of the secured end portion of a prop, constructed in accordance with this invention,

Figure 3 is a view in side elevation and partly in section of the prop when applied, and,

Figure 4 is a perspective view of the prop spring.

Referring to the drawings more particularly in Figure 1, 10 indicates generally a garage structure and 11 a pair of doors therefor which are hinged to swing to open position as illustrated. I have illustrated a prop of my invention applied to each door 11.

Each prop includes a channel clip generally designated by the reference character 12. The clip may have its side flanges 13 rounded as shown, and its bridge portion secured to the inner side of a door by screws 15 or other suitable means. Between the side flanges 13 there is pivoted the one end of a pipe or bar 16, said pipe having its pivoted end flattened as shown, and said flattened end being provided with a suitable opening for receiving the pivot bolt 17 which is extended through suitable openings

in flanges 13 and is removably held in position by a nut 18. A bushing 18' is fitted upon bolt 17, and spacing washers 19 may be employed for holding the pivoted end of pipe 16 against lateral movement. The side flanges 13 may also be provided with lugs 20 to limit the downward swinging movement of the pipe 16. A rivet or bolt 22 may be employed for limiting the upward swinging movement of the bar or pipe 16.

The pivoted end of pipe or bar 16 is formed with a slight protrusion 23 which is provided with a slot 24 which terminates at its inner end in a circular opening 25 in which there may be fitted a bushing 25'.

A spring generally designated by reference character 26 and specifically shown in Figure 4 is provided, said spring being made from spring wire of relatively large cross-section and bent to form the two substantially rectangular portions 27 and 28 and the intermediate tension loops 26. The portion 28 is slightly curved as shown. The outer end of the portion 28 is positioned in the opening 25 of the bar or pipe 16 while the similar end of the portion 27 is positioned in a U-shaped clip 30 struck from the bridge portion 14 of the channel clip 12.

The free end of the pipe or bar 16 is provided with a flattened and pointed end portion 31 and upon said portion 2 preferably secured by rivets or the like an L-shaped member 32. The member 32 serves as a weight for the free end of the bar or pipe 16.

In the use of the present invention the bar or pipe 16 is swung downwardly as shown in Figure 1, when it is desired to maintain the associated door in open position. The weight of the bar combined with tension of spring 26 causes the free and pointed end of the bar to penetrate the ground and provide a solid and strong prop for holding the door against closing. It will be noted with the bar 16 in lowered position that the spring portion 28 engages the forward edge of opening 25 and thus causes pressure to swing the bar in a downward direction. When the bar 16 is manually swung upwardly a certain degree the spring portion 28 will engage the rear edge of opening 25 and then cause a pressure for swinging the bar or pipe 16 upwardly and thus hold the same in an elevated and unobstructing position as also illustrated in Figure 1. It is obvious my form of prop can be

secured to a door in a short interval of time and that the same will serve in a positive manner to maintain a door in an open position.

5 I claim:

1. A door prop comprising a bar having an outer ground engaging end, means for pivotally mounting the inner end of the bar on a door, said bar having an extension 10 provided with a slot located inwardly of the pivotal point of the bar, a spring having one end secured to the pivotal mounting and the other end thereof received in the slot, the spring intermediate the ends thereof being 15 bent and provided with a tensioning coil, the spring exerting pressure on the extension of the bar and tending to move the free end of the bar to a raised or lowered position, the bent spring and tensioning coil 20 increasing the pressure on the inner end of the bar.

2. A door prop comprising a bar, a channel clip adapted to be secured to a door, means for pivoting one end of the bar between the side portions of the clip, the opposite end of the bar being provided with a ground engaging end, the bar at one side of the pivotal point being provided with an extension, said extension having a slot, a U-shaped spring having its legs rigidly secured to the clip, the free end of the spring being located in the slot at one side of the pivot point of the bar, the legs of the spring being bent intermediate their ends and provided with a tensioning coil, the free end of the spring exerting a pressure on the extension of the bar for maintaining the free end of the bar either in a lowered or raised position, the bent legs and tensioning coils increasing the pressure of spring on the inner 25 end of the bar. 30 35 40

EDWARD H. BOBO.
